ILLUMINATING DEVICE FOR INSPECTION
OF CONTENTS OF BOTTLES

Paul K. Wehmiller, Kirkwood, and William J. Nekola, Normandy, Mo., assignors to Barry-Wehmiller Machinery Company, St. Louis, Mo., a corporation of Missouri

Application June 30, 1949, Serial No. 102,348

1 Claim. (Cl. 88—14)

1 This invention relates to devices for inspection of contents of bottles and the like, and more particularly to an illuminated device which exposes foreign particles or impure conditions in the contacts of traveling bottles, jars and other transparent or translucent containers.

Prior to our invention, a commonly used inspection apparatus has included a lamp located at the rear of traveling bottles, directly opposite the eyes of the inspector, which results in a highly objectionable glare affecting the eyes and reducing the efficiency of the inspection. Under such conditions, an inspector is required to take rather frequent rests to relieve eye strains which not only impair his faculty for prolonged inspection, but may also tend to generally affect his vision.

An object of the present invention is to more clearly expose foreign particles and other objectionable conditions in the containers, thereby increasing the accuracy of the inspection, while greatly reducing the eye strain. Another object is to provide for a relatively long inspection time, permitting prolonged examinations of bottles wherein the contents may appear doubtful.

In the preferred form of the invention, a lamp device is beamed to produce a very clear lighted effect throughout the contacts of traveling bottles, which appear as the brightest objects in the visual field of the inspector. The lamp device never casts its rays of light directly into the eyes of the operator, and there is no distracting nearby glare to tire and confuse the operator's vision. Under these conditions, traveling bottles can be accurately inspected in a very short period of time to meet the present high production speeds, while avoiding the usual excessive eye strains.

With the foregoing and other objects in view, the invention comprises the novel combination and arrangement of specific details shown in the accompanying drawings, which illustrate a desirable form of the invention. However, it is to be understood that the scope of the invention extends to variations and modifications covered by terms of the claims hereunto appended.

Fig. 1 is a front view of an inspection device embodying features of this invention, including a diagrammatical illustration of a traveling conveyor.

Fig. 2 is a side view, with the conveyor shown in cross section.

As a conventional illustration of a traveling conveyor, we have shown a portion of a simple belt 3 arranged in a horizontal plane and movable in the direction indicated by arrows in Fig. 1.

2 said belt being supported on horizontal angle bars 4. However, the conveyor may be of any suitable type adapted to carry bottles or the like at any desired speed from a source of supply and through the inspection zone. For example, an ordinary endless belt conveyor may be employed.

We have shown upright bottles B seated on the traveling conveyor belt 3. In actual practice, for high speed production, the bottles can be very close together as very little time is required for accurate inspection.

5 5 designates a horizontally elongated background located at one side of, but substantially separated from the conveyor 3. To avoid a glaring reflection of light and also aid the inspector's vision, this background may have a dull surface, by which is meant a surface without gloss or sheen. In practice it is a dull wheat color, or **10** a pastel tan or green. A horizontally elongated elevated hood 6 is located above the space between the conveyor 3 and background 5 to receive a suitable illuminating device, said hood being open at the bottom to direct rays of light downwardly **15** toward the traveling conveyor.

The illuminating device herein shown comprises a series of inclined electric lamps 7 arranged within the elongated elevated hood, the center lines of said lamps being inclined in a direction toward the conveyor 3, as suggested at 8 in Fig. 2, so as to direct inclined beams of light to the bottles on the conveyor.

20 The elevated hood shown in the drawings has a rear wall member 9 extending upwardly from the background 5, a top wall member 10 extending forwardly from said rear wall member, and an inclined front baffle wall 11 extending downwardly from the top wall member. The background 5 and the wall members 9, 10 and 11 can be conveniently formed by a single sheet of material bent to the shape shown in Fig. 2, and suitably connected to vertically elongated end walls 12. The front baffle member 11 terminates in a line substantially above the conveyor 3 to conceal the lamps from the inspector and provide an open space for the traveling bottles. The conveyor 3 is lower than the inclined lamps 7, where it will not intercept the light projected directly from the elevated lamps to the bottles. In this unique device, the advantage of extreme simplicity coupled with very high efficiency is gained by deliberately avoiding the use of any device which would alter the effect of the illumination in the clear, unobstructed space in front of the background wall 5.

To illustrate a simple adjustable support for the elevated hood and its lamps, we have shown an elongated horizontal bar 13 having upturned ends 14 connected to the end walls 12, a post 15 extending downwardly from said bar 13, and a base 16 telescoped with the lower end portion of said post to provide for upward and downward adjustments of the background, hood and lamps with relation to the horizontal conveyor 3. The tubular upper portion of the base 16 is split and provided with ears 17 to receive a clamping bolt 18 whereby the background, hood and lamps are secured in positions to which they are adjusted. However, it is to be understood that other suitable adjustable elements may be employed for convenience in accurately locating the inspection device during its initial installation, and also in making selective adjustments for clear and easy inspection of the contents of bottles, jars, and the like, having various different dimensions.

In Fig. 2, an eye of the inspector is suggested at 19, with an inclined line 20 leading therefrom to the bottom of the baffle wall 11 which conceals the elevated lamps from the visual field. The inclined beams of light are directed away from the background 5 and projected downwardly onto rear portions of the traveling bottles, thereby effectively illuminating the contents of the bottles. In this arrangement, the top faces of shoulders of the bottles are directly exposed to downwardly projected rays of light, and this specific condition enhances the lighting effect throughout the contents of the bottles. Foreign particles and impure conditions are very clearly exposed, so the usual inspections can be easily made with a high degree of accuracy, and in very brief periods of time. However, a doubtful bottle can be subjected to prolonged inspection while it progresses through the elongated inspection zone, while the conveyor travels at a relatively high speed to provide for the usual rapid inspections.

In actual commercial practice, the new device has been successfully employed on a large scale to inspect beer (an amber fluid) in amber bottles, with the result of actually obtaining the aforesaid outstanding advantages.

We claim:

An illuminating device for use at the rear side of a conveyor whereon transparent containers are presented for inspection, said device comprising a vertically directed wall having a relatively light colored dull surface extending above the level of the conveyor and spaced from the conveyor to provide a clear space in front of said wall surface, a hood positioned across the upper portion of said wall directly above said clear space, said hood having a front inclined wall portion located with its lower free edge spaced above the rear side of the conveyor and clear of the top of the containers presented for inspection, and illuminating means located within said hood behind said inclined wall portion above the lower free margin thereof, said hood and inclined wall portion cooperating to direct the light without obstruction downwardly across said dull surface and behind the transparent containers, and said light colored dull surface cooperating with said illuminating means to back-light the transparent containers uniformly.
